FOUNDRYMAN'S GLOVE

Isadore Singer, Chicago, Ill., assignor to Singer Glove Manufacturing Company, Chicago, Ill., a corporation of Illinois

Application October 7, 1953, Serial No. 384,610

4 Claims. (Cl. 2—158)

The present invention relates to an improved protective glove or mitt particularly devised for the use of foundrymen and others who handle hot objects. Although the glove has wide adaptability for use in many industries where wear-resistant hand coverage which protects against heat and flame is needed, nevertheless, a particular phase of everyday foundry operation best illustrates its special suitability in this regard. This is in the handling of red hot castings as freed from a sand mold in which they are cast.

The castings have an upstanding sprue representing the waste piece in the passage through which the molten metal is poured into the interior of the mold, and it is the custom of the foundryman, his hand protected by some sort of work glove, to grasp this sprue rapidly and pull it to one side or the other, dislodging it from the remainder of the casting. Even if the foundryman's glove palm is protected by a suitable layer of asbestos or other flame proofing material, or if a separate protective pad of such material is used, one or more such operations quickly heats the glove palm to an extreme degree, highly uncomfortable to the workman's hand since, as is known, asbestos and like flame-resistant materials are not non-conductors or heat insulators.

It is therefore desirable that the foundryman be enabled to obtain relief from this excessive heat by freeing his fingers and palms therefrom while they can cool. It is further desirable that this be possible without requiring complete removal of the glove since it is evident that the operation, repeated many times, will represent an excessive waste of time.

It is therefore an object of the invention to provide a simple and inexpensive protective work glove which affords a flame-resistant layer of asbestos or equivalent material at the palm and fingers thereof to safeguard a foundryman against burns in the usual sprue removing operation. This glove is provided with a relatively large opening at the rear hand and knuckle area thereof, through which the hand may be rapidly withdrawn and the glove also has a loose wrist strap of flexible material attached thereto above the opening, which strap supports the glove as it dangles from the workman's wrist. Accordingly, the glove may be quickly and easily replaced on the hand after the necessary cooling period.

A more specific object of the invention is to provide a foundryman's work glove as outlined above, in which a finger and palm protective portion is provided with a relatively wide, loose wrist strap of relatively large girth which is attached to the glove or mitt immediately behind a relatively large free opening through which the fingers and palm may be withdrawn quickly and easily, allowing the glove or mitt to dangle from the worker's wrist as it and his palm cool. The wrist strap is attached to the remainder of the glove in a very flexible manner enabling the remainder of the glove to drop freely away from the hand just as soon as the fingers and palm are freed therefrom. Yet the relation of the strap to the glove is such as to cause the butt of the latter to tend to

2

dig into the under surface of the wrist as the glove dangles, inhibiting its complete separation from the user's arm. Thus the glove is held conveniently accessible for replacement when desired.

5 A still further specific object is to provide an improved glove or mitt of the sort described above in which the width of the flexible wrist strap extends substantially to the rear of its connection to the remainder of the glove. In this way a glove dangling limply from the wrist strap tends to engage against the inner surface of the user's wrist or the butt of his hand and to resist accidental dropping from the wrist.

10 The foregoing statements are indicative in a general way of the nature of the invention. Other and more specific objects will be apparent to those skilled in the art upon a full understanding of the construction and use of the glove.

15 A single embodiment of the invention is presented here-in for purpose of illustration. It will be appreciated that 20 the invention may be incorporated in other modified forms coming equally within the scope of the appended claims.

In the drawings:

25 Fig. 1 is a bottom plan view, partially broken away, of the improved foundryman's glove, generally illustrating the character and relationship of parts thereof;

Fig. 2 is a view in transverse section along a line corresponding to line 2—2 of Fig. 1, showing the laminated composition of the various panels of the glove;

30 Fig. 3 is a top plan view further illustrating the structural relation of a flexible wrist strap to other parts of the glove; and

Fig. 4 is a fragmentary perspective view illustrating the way in which the glove is specially designed to be used.

35 Referring first to Figs. 1, 2 and 3, the improved glove or mitt 10 is in general constituted by an inner palm protecting pad 11 of asbestos which is of substantial area, providing a large finger protecting area 12 and a somewhat smaller thumb protecting area 13. The pad is firmly secured to a finger, thumb and palm covering panel 14 by lines of stitching 15. Panel 14 may be a suitable leather such as buckskin or other appropriate rugged wear-resisting material. An internal layer 16 of fabric comfortable to the touch, of shape and size approximately corresponding to panel 14, is disposed inwardly of that panel to afford an inner finger, palm and thumb panel contacting the hand of the wearer.

40 Leather panel 14 and fabric panel 16 are suitably shaped and stitched to afford a thumb 17, metal staples 50 18 being employed for this purpose in the embodiment of the invention illustrated, and asbestos thumb area 13 is stitched to the thus formed member.

45 A rear knuckle covering panel 19 (Figs. 2 and 3) is appropriately shaped to fit the upturned sides 20 of the panels 14, 16, and is secured to these sides by staples 55 18. Thumb member 17 and one side 20 are united by a generally triangular bridge piece 21 of leather secured to the respective members by staples 18, and an end tongue 22 of this bridge piece is brought around into the palm area, as illustrated in Fig. 1, and stapled to leather panel 14.

50 The rear finger and knuckle panel 19 affords needed heat and scuff protection for the fingers of the user, also assisting in holding the mitt on the user's hand, and the last named function is furthered by a relatively narrow cross strap 23 of leather, stapled at its end to the bridge piece 21 and to the upwardly shaped opposite side 20 of palm panel 14.

55 The improved glove is completed by a wrist strap 24 of substantial width secured in an annular band-like outline by staples 18, as illustrated in Fig. 3. This strap is relatively loose, sufficiently extensive in girth to receive

freely the fingers and fist of the user when the glove is donned. The strap is secured to the rear extremity of palm panel 14 in such position that the major portion of the width of the strap extends rearwardly or outwardly of panel 14.

A relatively wide throat opening 26 is provided between opposite sides 20 of the panel, at the ends of the line of staples which secure the strap to the panel, and a large opening 27 forwardly adjoins the throat. Furthermore, the strap is very flexibly connected to the remainder of the glove; accordingly, when the palm and fingers of the user are rearwardly withdrawn through opening 27, the glove can be allowed to dangle loosely from the user's wrist, as illustrated in Fig. 4, while the glove and the user's palm are cooled. Yet the stapled line of connection of strap 25 permits the rear or butt portion of the glove palm to swing into a mild gripping engagement with the inner surface of the user's wrist, or with the butt of his hand, so that the glove may be suspended vertically from the wrist without dropping off.

Should the user desire to fully remove the glove, this is quickly done due to the relatively large perimeter of the wrist strap 24, and the hand can be just as quickly and easily reinserted into the glove, as from the position of Fig. 4, because of the looseness and flexibility of knuckle strap 23.

I claim:

1. A protective work glove comprising a forward hand receiving member formed in its entirety of flexible material and consisting of a first palm and finger panel and a second knuckle panel bridging opposite margins of the same, said first panel having plural laminations including a layer of combustion resistant material secured in external covering relation to a large portion of the area thereof, said opposite margins of said first panel being substantially spaced from one another rearwardly of said second panel to provide an open throat of substantial width adjacent the rear extremity of said first panel, and a flexible wrist band of substantial width secured to said first panel across said rear extremity thereof, said wrist band being of sufficient girth to bridge said open throat in a loose outline.

2. A protective work glove comprising a forward hand receiving member formed in its entirety of flexible material and consisting of a first palm and finger panel and a second knuckle panel bridging opposite margins of the same, said first panel having plural laminations including a layer of combustion resistant material secured in external covering relation to a large portion of the area thereof, said opposite margins of said first panel being substantially spaced from one another rearwardly of said second panel to provide an open throat of substantial

width rearwardly thereof, and a flexible wrist band of substantial width secured to said first panel across the rear extremity thereof, said wrist band being of sufficient girth to bridge said open throat in a loose outline, said band extending substantially to the rear of the rear extremity of said first panel.

3. A protective work glove comprising a forward hand receiving member formed in its entirety of flexible material and including a first palm and finger panel and a second knuckle panel bridging opposite margins of the same forwardly thereof, said first panel having plural laminations including a layer of asbestos material secured in external covering relation to a large portion of the face area thereof, said opposite margins of said first panel being substantially spaced from one another rearwardly of said second panel to provide an open throat of substantial width adjacent the rear extremity of said first panel, and a flexible wrist band of substantial width secured along its inner margin to the outer margin of the rear extremity of said first panel and extending continuously across the back thereof in loose outline to define the lower extremity of said throat.

4. A protective work glove comprising a forward hand receiving member formed in its entirety of flexible material and including a first palm and finger panel and a second knuckle panel bridging opposite margins of the same forwardly thereof, said first panel having plural laminations including a layer of asbestos material secured in external covering relation to a large portion of the face area thereof, said opposite margins of said first panel being substantially spaced from one another rearwardly of said second panel to provide an open throat of substantial width adjacent the rear extremity of said first panel, a flexible wrist band of substantial width secured along its inner margin to the outer margin of the rear extremity of said first panel and extending continuously across the back thereof in loose outline to define the lower extremity of said throat, and a protective strap bridging opposite margins of said first panel immediately rearwardly of said second panel to define the upper extremity of said throat.
